UNITED STATES PATENT OFFICE.

ENRIQUE TROYA, OF NEW YORK, N. Y.

DESIGN FOR A FINGER RING.

Application filed March 18, 1925. Serial No. 12,757. Term of patent 14 years.

To all whom it may concern:

Be it known that I, ENRIQUE TROYA, a citizen of the Republic of Ecuador, residing at New York city, in the county of New York and State of New York, have invented a new, original, and ornamental Design for Finger Rings, of which the following is a specification, reference being had to the accompanying drawing, forming part thereof.

Fig. 1 is a plan view of a finger ring showing my new design, the ring being shown parted transversely and spread flat;

Fig. 2 is a side elevation;

Fig. 3 is a transverse section on the line, 3—3, of Fig. 1, looking toward the right, it being assumed that the ring is in its circular form;

Fig. 4 is a transverse section on the line, 4—4, of Fig. 1, looking toward the right;

Fig. 5 is an elevation of the end of the ring which is uppermost in Figs. 1 and 2.

I claim:

The ornamental design for a finger ring, as shown.

ENRIQUE TROYA.
